CLAIM

We claim the ornamental design for a locking packaging container, as shown and described.

DESCRIPTION

FIG. 1 is a perspective view of a first embodiment of a locking packaging container in an open configuration, showing our new design;

FIG. 2 is a front view of the first embodiment of a locking packaging container in an open configuration;

FIG. 3 is a rear view of the first embodiment of a locking packaging container in an open configuration;

FIG. 4 is a right view of the first embodiment of a locking packaging container in an open configuration;

FIG. 5 is a left view of the first embodiment of a locking packaging container in an open configuration;

FIG. 6 is a top view of the first embodiment of a locking packaging container in an open configuration;

FIG. 7 is a bottom view of the first embodiment of a locking packaging container in an open configuration;

FIG. 8 is a perspective view of the first embodiment of a locking packaging container in a closed configuration;

FIG. 9 is a front view of the first embodiment of a locking packaging container in a closed configuration;

FIG. 10 is a rear view of the first embodiment of a locking packaging container in a closed configuration;

FIG. 11 is a right view of the first embodiment of a locking packaging container in a closed configuration;

FIG. 12 is a left view of the first embodiment of a locking packaging container in a closed configuration;

FIG. 13 is a top view of the first embodiment of a locking packaging container in a closed configuration;

FIG. 14 is a bottom view of the first embodiment of a locking packaging container in a closed configuration;

FIG. 15 is a perspective view of a second embodiment of a locking packaging container in an open configuration;

(Continued)

FIG. 16 is a front view of the second embodiment of a locking packaging container in an open configuration; FIG. 17 is a rear view of the second embodiment of a locking packaging container in an open configuration; FIG. 18 is a right view of the second embodiment of a locking packaging container in an open configuration; FIG. 19 is a left view of the second embodiment of a locking packaging container in an open configuration; FIG. 20 is a top view of the second embodiment of a locking packaging container in an open configuration; FIG. 21 is a bottom view of the second embodiment of a locking packaging container in an open configuration; FIG. 22 is a perspective view of the second embodiment of a locking packaging container in a closed configuration; FIG. 23 is a front view of the second embodiment of a locking packaging container in a closed configuration; FIG. 24 is a rear view of the second embodiment of a locking packaging container in a closed configuration; FIG. 25 is a right view of the second embodiment of a locking packaging container in a closed configuration; FIG. 26 is a left view of the second embodiment of a locking packaging container in a closed configuration; FIG. 27 is a top view of the second embodiment of a locking packaging container in a closed configuration; and, FIG. 28 is a bottom view of the second embodiment of a locking packaging container in a closed configuration. The evenly spaced broken lines depict portions of the locking packaging container that form no part of the claimed design.
